DESIGN FOR A HANDLE FOR RODS FOR FLY OR BAIT CASTING

Lloyd P. Wallace, Ferguson, Mo.

Application February 26, 1948, Serial No. 144,743

Term of patent 14 years

(Cl. D31—4)

To all whom it may concern:

Be it known that I, Lloyd P. Wallace, a citizen of the United States, residing in the city of Ferguson, county of St. Louis, and State of Missouri, have invented a new, original, and ornamental Design for a Handle for Rods for Fly or Bait Casting, of which the following is a specification, reference being had to the accompanying drawing, forming a part thereof.

In the drawing:

Fig. 1 is a plan view of the upper or outer end of the handle;

Fig. 2 is a side elevation of the handle;

Fig. 3 is a further side elevational view of the handle, when rotated a quarter turn from the position shown by Fig. 2, and

Fig. 4 is a further side elevational view of the handle when rotated a half turn about its axis,

from the position shown by Fig. 3, each view showing the handle embodying my new design.

I claim:

The ornamental design for a handle for rods for fly or bait casting, substantially as shown.

LLOYD P. WALLACE.
